UNITED STATES PATENT OFFICE

JAMES B. HOLSTON, OF DAYTON, OHIO, ASSIGNOR TO THE HUFFMAN MANUFACTURING COMPANY, OF DAYTON, OHIO, A CORPORATION OF OHIO

FOOT VALVE EXTRACTOR

Application filed May 13, 1931. Serial No. 537,058.

This invention relates to an apparatus for delivering liquid from an underground reservoir, such as is used in connection with gasoline dispensing pumps, and more particularly to what is commonly known as a foot valve extractor fitting. The reservoirs or storage tanks for gasoline pumps are usually buried a considerable distance underground, and often under concrete, and the suction pipe which connects the reservoir with the pump is provided at or near its lower end with one or more valves to prevent the reverse flow of liquid through the same and thus maintain the suction or discharge pipe full of liquid between operations of the pump. If these valves are injured or foreign matter accumulates on the valve seat to such an extent that the valves do not properly seat there is a leakage of gasoline from the suction pipe which often results in inaccurate measurement of the liquid delivered by the pump. In order to permit the valves to be repaired or cleaned without the necessity of digging down to the tank it has been proposed heretofore to provide means for removably supporting the suction pipe in such a manner that the pipe and its valve can be readily removed. For this purpose an outer casing is usually provided which extends from a point near the ground level down to the reservoir, with which it is connected. The suction pipe is removably supported within this casing and means are provided for establishing communication between the same and a conduit which leads from the casing to the pump.

One object of the present invention is to provide an apparatus of this character which will be simple and relatively inexpensive in construction and from which the pipe and its valve may be readily removed.

A further object of the invention is to provide such an apparatus in which the suction pipe will be directly connected with the conduit leading to the pump so that no liquid will enter the casing itself.

A further object of the invention is to provide means which may be easily operated from the upper end of the casing for connecting the suction pipe with and disconnecting the same from the conduit.

A further object of the invention is to provide such an apparatus with means for so connecting the casing with the reservoir as to permit of the slight relative movement of these parts.

Other objects of the invention will appear as the apparatus is described in detail.

In the accompanying drawings Fig. 1 is a longitudinal sectional view of an apparatus embodying my invention; Fig. 2 is a transverse section taken on the line 2-2 of Fig. 1; Fig. 3 is a transverse section taken on the line 3-3 of Fig. 1; and Fig. 4 is an end elevation of the elbow of the suction pipe and its actuating device.

In these drawings I have illustrated one embodiment of the invention and have shown the same as comprising a casing 5 which comprises a tubular lower portion 6 adapted to be connected with an underground reservoir 7, and a cast upper portion or fitting 8, the upper end of which is located at or adjacent to the ground level and is normally closed by a cap 9. As here shown, the fitting or upper portion of the casing 8 has at its lower end a boss 10 into which the upper end of the tubular portion 6 is screw threaded. The tubular portion 6 of the casing is of relatively large diameter and arranged within the same is the suction pipe 11 which extends through this lower portion of the casing and into the reservoir 7 where it is provided with a foot valve 12, it being in the present instance a double poppet foot valve. If desired, the suction pipe may be provided at a point above the reservoir with a check valve 13. The number and arrangement of the valves is optional, either the foot valves or the check valve, or both, may be used. The suction pipe 11 is provided within the upper part 8 of the casing with a laterally extending outlet which preferably is in the form of an elbow 14 having screw threaded connection with the upper end of the pipe. Extending laterally from opposite sides of this elbow

are studs 15 which rest upon inwardly extending lugs 16 carried by, and arranged on opposite sides of, the casting or upper part of the casing 8. The studs and lugs thus serve to removably support the pipe within

the casing but permit the same to have a limited amount of lateral movement with relation to the casing. A conduit 17 extends from the upper part of the casing to the pump and, in the present instance, comprises an elbow 18 arranged exteriorly of but extending through the wall of the casing. The inner end of this elbow has a tapered seat 19 adapted to be engaged by the outer end of the outlet or elbow 14 of the pipe 11, the elbow 14 being preferably provided with a tapered gasket 20 of brass or other suitable material to provide a sealed or tight joint between the pipe 11 and the conduit 17. The conduit may be of any suitable character. The inwardly extending portion thereof, which is provided with the seat, is not necessarily formed separate from the upper part 8 of the casing but in the preferred construction here shown the elbow 18 of the conduit is rotatably mounted in a suitable opening in the casing so that the conduit may be led at various angles from the casing. It will be noted also that the seat 19 is vertically arranged so that there will be little or no tendency for dirt or foreign matter to accumulate thereon and thus prevent a tight joint from being formed.

Any suitable means may be employed for pressing the elbow 14 against the inner end of the conduit and for holding the same in firm engagement therewith but this means is preferably of such a character that it may be manipulated from the upper end of the casing and it is also desirable that it should be of such a character that it may be utilized for lifting the pipe out of the casing after it has been disconnected from the conduit. In the construction here shown I employ for this purpose a toggle, one arm 21 of which is bifurcated and the two branches thereof pivotally connected with the respective sides of the elbow 14, as shown at 22. The other arm 23 of the toggle is arranged to bear against the side wall of the casing which thus forms a stop against which the toggle acts so that the movement of the toggle toward its straight position will press the elbow 14 firmly into engagement with the seat 19 of the elbow. Preferably the housing is provided with a vertical groove 24 to receive the end of the arm 23 of the toggle, and thus guide the elbow into proper alignment with the end of the conduit. Connected with the toggle, at the point of connection of the two arms thereof, is an actuating device which, in the form here shown, comprises a lower member or rod 25 connected with the toggle and an upper member 26 having a socket 27 into which the upper end of the rod 25 is screw threaded. The upper member 26 of the actuating device is rotatably supported and is held normally against upward movement so that when rotated in one direction it will tend to extend the toggle and will exert a powerful pressure thereon. As here shown, the upper member

26 of the actuating device is rotatably mounted in a cross bar 28 which is adapted to engage beneath the opposed lugs 29 extending inwardly from opposite sides of the casing near the top thereof. The cross bar preferably has an elongated slot 30 through which the actuating member 26 extends and in which it may have sufficient lateral movement to accommodate it to the changing positions of the toggle. The member 26 is held against upward movement with relation to the cross bar by means of a washer 31 seated on a shoulder on the member 26. It is preferably also held against downward movement with relation to the cross bar by a washer 32 and a nut 33. The actuating member 26 may be rotated in any suitable manner but is here shown as having a squared upper end 34 to receive a socket wrench or the like. The lugs 29 on the casing are so arranged that by turning the cross bar 28 to a position transverse to that shown in the drawings it will be disengaged from the lugs and may be lifted out of the casing. The actuating device and toggle being connected, respectively, with the cross bar and with the pipe it will be apparent that this cross bar may be utilized as a handle to lift these parts from the casing. If desired, a stop, such as that shown at 35, may be provided on the inner wall of the casing to prevent the movement of the toggle arm 21 beyond a vertical position.

The lower or tubular portion 6 of the casing may be connected with the reservoir in any suitable manner but it is desirable that this connection should be extensible to permit of a slight relative movement of the parts, such as might be produced by the sinking or settling of the tank, or to permit the connection to be established should there be a slight variation in the estimated distance between the top of the tank and the surface of the ground. For this purpose I have provided a special form of extensible coupling which comprises a tubular fitting 36 adapted to be screw threaded on a nipple 37 on the reservoir and surrounding the openings 38 through which the pipe 11 extends. The lower end of the tubular portion 6 of the casing extends into this tubular fitting and is slidably supported therein. The relative movement of the two parts is limited by a stop, such as a set screw 39, which extends through the fitting 38 and into a relatively wide circumferential groove 40 near the lower end of the portion 6 of the casing. The upper part of the fitting is formed with a circumferential recess 41 in which is located an expandible packing 42, here shown as U-shaped in cross section, and an annular wedge 43 extends between the two parts of this U-shaped packing and is pressed into the same by a spring 44 which is confined between the wedge and a cap 45 screw threaded onto the fitting.

While it is usually desirable to use a lower tubular member, as shown at 6, this is not always necessary and where conditions permit the member 6 may be omitted and the boss 10 of the upper member 8 screwed directly on the nipple 37 of the tank.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. In an apparatus for delivering liquid from an underground reservoir, a tubular casing adapted to be connected to said reservoir with its upper end adjacent to the ground level, a pipe removably supported in said casing, extending into said reservoir and having a laterally extending outlet near the upper end thereof, a valve in said pipe, a conduit leading from said casing and having one end arranged to be engaged by said outlet of said pipe to establish a tight connection between said parts, and means for imparting lateral movement to said pipe to cause said outlet to engage said end of said conduit.

2. In an apparatus for delivering liquid from an underground reservoir, a tubular casing adapted to be connected to said reservoir with its upper end adjacent to the ground level, a pipe extending through the lower portion of said casing and into said reservoir, a valve in said pipe, an elbow connected with the upper end of said pipe, said casing and said elbow having interengaging parts to removably support said pipe in said casing, a conduit extending through the wall of said casing and having its inner end arranged to be engaged by said elbow to form a tight connection between said parts, and means for moving said elbow into engagement with said end of said conduit.

3. In an apparatus for delivering liquid from an underground reservoir, a tubular casing adapted to be connected to said reservoir with its upper end adjacent to the ground level, a pipe removably supported in said casing, extending into said reservoir and having an elbow at the discharge end thereof, a conduit extending through a wall of said casing, the inner end of said conduit and the outer end of said elbow being shaped for sealing engagement one with the other, and operable means to move said elbow into and hold the same in tight engagement with said conduit.

4. In an apparatus for delivering liquid from an underground reservoir, a tubular casing adapted to be connected to said reservoir with its upper end adjacent to the ground level, a pipe removably supported in said casing, extending into said reservoir and having an elbow at the discharge end there-

of, a conduit extending through a wall of said casing, the inner end of said conduit and the outer end of said elbow being shaped for sealing engagement one with the other, and an operable device arranged between said elbow and that side of said casing opposite said conduit to press said elbow into tight engagement with said conduit.

5. In an apparatus for delivering liquid from an underground reservoir, a tubular casing adapted to be connected to said reservoir with its upper end adjacent to the ground level, a pipe removably supported in said casing, extending into said reservoir and having an elbow at the discharge end thereof, a conduit extending through a wall of said casing, the inner end of said conduit and the outer end of said elbow being shaped for sealing engagement one with the other, and an operable device connected with said elbow and acting on a wall of said casing to press said elbow against the end of said conduit.

6. In an apparatus for delivering liquid from an underground reservoir, a tubular casing adapted to be connected to said reservoir with its upper end adjacent to the ground level, a pipe extending through the lower portion of said casing and into said reservoir, a valve in said pipe, an elbow connected with the upper end of said pipe, said casing and said elbow having interengaging parts to removably support said pipe in said casing at a point spaced from the upper end thereof, a conduit extending through the wall of said casing, the inner end of said conduit and outer end of said elbow being shaped for sealing contact one with the other, an operable device to press said elbow against said conduit, and means arranged adjacent to the upper end of said casing for actuating said operable device.

7. In an apparatus for delivering liquid from an underground reservoir, a tubular casing adapted to be connected to said reservoir with its upper end adjacent to the ground level, a pipe extending through the lower portion of said casing and into said reservoir, a valve in said pipe, an elbow connected with the upper end of said pipe, said casing and said elbow having interengaging parts to removably support said pipe in said casing at a point spaced from the upper end thereof, a conduit extending through the wall of said casing, the inner end of said conduit and outer end of said elbow being shaped for sealing contact one with the other, an operable device connected with said elbow and acting against the wall of said casing to press said elbow against said conduit, and an actuating device connected with said operable device for actuating the same and extending to a point near the top of said casing.

8. In an apparatus for delivering liquid from an underground reservoir, a tubular casing adapted to be connected to said reser-

- voir with its upper end adjacent to the ground level, a pipe extending through the lower portion of said casing and into said reservoir, a valve in said pipe, an elbow connected with the upper end of said pipe, said casing and said elbow having interengaging parts to removably support said pipe in said casing at a point spaced from the upper end thereof, a conduit extending through the wall of said casing, the inner end of said conduit and outer end of said elbow being shaped for sealing contact one with the other, an operable device connected with said elbow and acting against the wall of said casing to press said elbow against said conduit, an actuating device connected with said operable device for actuating the same and extending to a point near the top of said casing, and a part connected with said actuating device for lifting said actuating device, said operable device and said pipe from said casing.
9. In an apparatus for delivering liquid from an underground reservoir, a tubular casing adapted to be connected to said reservoir with its upper end adjacent to the ground level, a pipe extending through the lower portion of said casing and into said reservoir, a valve in said pipe, an elbow connected with the upper end of said pipe, said casing and said elbow having interengaging parts to removably support said pipe in said casing at a point spaced from the upper end thereof, a conduit extending through the wall of said casing, the inner end of said conduit and outer end of said elbow being shaped for sealing contact one with the other, a toggle having one arm connected with said elbow and having its other arm arranged to act on a wall of said casing, and an actuating device operatively connected with said toggle and having a part arranged near the upper end of said casing for imparting operative movement thereto.
10. In an apparatus for delivering liquid from an underground reservoir, a tubular casing adapted to be connected to said reservoir with its upper end adjacent to the ground level, a pipe extending through the lower portion of said casing and into said reservoir, a valve in said pipe, an elbow connected with the upper end of said pipe, said casing and said elbow having interengaging parts to removably support said pipe in said casing at a point spaced from the upper end thereof, a conduit extending through the wall of said casing, the inner end of said conduit and outer end of said elbow being shaped for sealing contact one with the other, a toggle having one arm connected with said elbow and having its other arm arranged to act on a wall of said casing, a member operatively connected with said toggle, a rotatable member having screw threaded engagement with the first mentioned member and extending to a point near the top of said casing and held against axial movement.
11. In an apparatus for delivering liquid from an underground reservoir, a tubular casing adapted to be connected to said reservoir with its upper end adjacent to the ground level, a pipe extending through the lower portion of said casing and into said reservoir, a valve in said pipe, an elbow connected with the upper end of said pipe, said casing and said elbow having interengaging parts to removably support said pipe in said casing at a point spaced from the upper end thereof, a conduit extending through the wall of said casing, the inner end of said conduit and outer end of said elbow being shaped for sealing contact one with the other, a toggle having one arm connected with said elbow and having its other arm arranged to act on a wall of said casing, a member operatively connected with said toggle, a cross bar removably connected with said casing near the upper end thereof and held normally against upward movement with relation to said casing, and a second member rotatably mounted in said cross bar and held against axial movement with relation thereto and having screw threaded connection with the first mentioned member.
12. In an apparatus for delivering liquid from an underground reservoir, a tubular casing adapted to be connected to said reservoir with its upper end adjacent to the ground level, a pipe extending through the lower portion of said casing and into said reservoir, a valve in said pipe, an elbow connected with the upper end of said pipe, said casing and said elbow having interengaging parts to removably support said pipe in said casing at a point spaced from the upper end thereof, a conduit extending through the wall of said casing, the inner end of said conduit and outer end of said elbow being shaped for sealing contact one with the other, a toggle having one arm connected with said elbow and having its other arm arranged to act on a wall of said casing, a member operatively connected with said toggle, said casing having opposed lugs near the upper end thereof, a cross bar adapted to be engaged beneath said lugs and having an opening therethrough, and a second member rotatably mounted in said opening, held against axial movement with relation thereto and having screw threaded connection with the first mentioned member.
13. In an apparatus for delivering liquid from an underground reservoir, a tubular casing adapted to be connected to said reservoir with its upper end adjacent to the ground level, a pipe extending through the lower portion of said casing and into said reservoir, a valve in said pipe, an elbow connected with the upper end of said pipe, said casing and said elbow having interengaging parts to removably support said pipe in said casing at a point spaced from the upper end thereof, a conduit extending through the wall of said casing, the inner end of said conduit and outer end of said elbow being shaped for sealing contact one with the other, a toggle having one arm connected with said elbow and having its other arm arranged to act on a wall of said casing, a member operatively connected with said toggle, a rotatable member having screw threaded engagement with the first mentioned member and extending to a point near the top of said casing and held against axial movement.

parts to removably support said pipe in said casing, said casing having an opening in the wall thereof adjacent to said elbow, a second elbow arranged exteriorly of said casing and having one end rotatably mounted in said opening, the adjacent ends of said elbows being shaped for sealing engagement one with the other, and means for moving the first mentioned elbow into engagement with said second elbow.

14. In an apparatus for delivering liquid from an underground reservoir, a tubular casing adapted to be connected to said reservoir with its upper end adjacent to the ground level, a pipe extending through the lower portion of said casing and into said reservoir, a valve in said pipe, an elbow connected with the upper end of said pipe, said casing and said elbow having interengaging parts to removably support said pipe in said casing, a conduit extending through a wall of said casing and having at its inner end a vertically arranged seat adapted to be engaged by said elbow, and means for moving said elbow into engagement with said seat.

15. In an apparatus for delivering liquid from an underground reservoir, a tubular casing adapted to be connected to said reservoir with its upper end adjacent to the ground level and having opposed lugs spaced from the upper end thereof, a pipe extending through the lower portion of said casing into said reservoir, a valve in said pipe, an elbow connected to the upper end of said pipe and having oppositely extending studs to engage the respective lugs on said casing and support said elbow thereon for transverse movement, a conduit extending through a wall of said casing and having its inner end arranged to be engaged by the outer end of said elbow, and means for moving said elbow into engagement with said conduit.

16. In an apparatus for delivering liquid from an underground reservoir, a casing having a tubular lower portion, a fitting adapted to be rigidly secured to said reservoir and to receive the lower end of said tubular portion of said casing, said fitting and said portion of said casing having cooperating parts to limit the relative longitudinal movement thereof, packing between said fitting and said portion of said casing, a pipe movably supported in said casing and extending into said reservoir, a conduit connected with said casing, and means for establishing communication between said pipe and said conduit.

17. In an apparatus for delivering liquid from an underground reservoir, a tubular fitting having means for securing the same to said reservoir about an opening therein, a casing having a tubular lower portion slidably mounted in said fitting and having a circumferential groove, a stop mounted on

said fitting and extending into said groove, packing between said fitting and said portion of said casing, a pipe removably supported in the upper portion of said casing and extending into said reservoir, a conduit leading from said casing, and means to establish communication between said pipe and said conduit.

18. In an apparatus for delivering liquid from an underground reservoir, a tubular fitting having means for securing the same to said reservoir about an opening therein, a casing having a tubular lower portion slidably mounted in said fitting and having a circumferential groove, a stop mounted on said fitting and extending into said groove, packing between said fitting and said portion of said casing, a pipe removably supported in the upper portion of said casing and extending into said reservoir, a conduit extending through a wall of said casing, and an elbow on the upper end of said pipe adapted to have sealing engagement with the inner end of said conduit, and means for moving said elbow into engagement with said conduit.

19. In an apparatus for delivering liquid from an underground reservoir, a tubular fitting having means for securing the same to said reservoir about an opening therein, a casing having a tubular lower portion slidably mounted in said fitting and having a circumferential groove, a stop mounted on said fitting and extending into said groove, said fitting having a recess extending about said portion of said casing, an expansible packing arranged in said recess, an expanding member engaging said packing, a spring acting on said expanding member, a pipe removably supported in the upper portion of said casing and extending into said reservoir, a conduit leading from said casing, and means to establish communication between said pipe and said conduit.

In testimony whereof, I affix my signature hereto.

JAMES B. HOLTSON.
